[57] **CLAIM**

The ornamental design for a police gripper, as shown and described.

DESCRIPTION

FIG. 1 is a front elevational view of a police gripper showing my new design;

FIG. 2 is a right side elevational view thereof;

FIG. 3 is a rear elevational view thereof;

FIG. 4 is a perspective view in operative position; the broken line showing of a hand is for illustrative purposes only;

FIG. 5 is a bottom plan view of FIG. 1; and

FIG. 6 is a top plan view of FIG. 1.
